UNITED STATES PATENT OFFICE.

GEORGE T. BARR, OF WACO, TEXAS.

BUTTONHOLE CUTTER OR SHEARS.

No. 881,890.

Specification of Letters Patent. Patented March 17, 1908.

Application filed October 16, 1907. Serial No. 397,710.

To all whom it may concern:

Be it known that I, GEORGE T. BARR, a citizen of the United States, residing at Waco, in the county of McLennan and State 5 of Texas, have invented certain new and useful Improvements in Buttonhole Cutters or Shears, of which the following is a specification, reference being had to the accompanying drawings.

10 My invention relates to improvements in button hole cutters or shears and more particularly to an improved adjustable stop device for regulating the cutting action of the blades whereby button holes of different 15 lengths may be cut.

The object of the invention is to provide an adjustable stop or regulating means of this character for the pivoted arms or members of button hole cutters, shears and similar instruments or tools, which will be simple 20 and inexpensive in construction, strong and durable in use and convenient and easy to operate.

With the above and other objects in view, 25 the invention consists of the novel features of construction hereinafter described and claimed, and illustrated in the accompanying drawings, in which

Figure 1 is a perspective view of a button 30 hole cutter provided with my improved stop device; Fig. 2 is a front elevation of the same, parts being in section; Fig. 3 is a detail section taken on the plane indicated by the line 3—3 in Fig. 2; and Fig. 4 is a detail 35 section taken on the plane indicated by the line 4—4 in Fig. 3.

In the drawings 1 denotes a button hole 40 cutter or shears of well known form consisting of two arms 2, 3, pivotally connected at 4 and having finger pieces or loops 5 at one end and co-acting cutting blades 6 at the opposite end. The blades 6 are of the usual form and are preferably arranged at right angles to the plane of the arms or members 45 2, 3, so that vertical button holes or button holes which are parallel with the edge of the button hole flap may be conveniently and easily cut as will be readily understood.

My improved means for varying and limiting 50 the cutting action of the blades comprises a stop screw 7 and an operating wheel 8. These parts are arranged in an enlarged portion 9 which is formed upon the inner edge of the arm 2 and adapted to enter a 55 similar shaped recess 10 formed in the corresponding portion of the other member 3,

when the two parts are brought together to close the blades. In the enlargement 9 is formed an angularly arranged notch or slot 10^a adapted to receive the wheel 8 so as 60 to allow the latter to rotate freely therein. In said portion or enlargement 9 is also formed an angularly arranged hole or opening 11 which intersects the slot 10^a adjacent to its center and which has its inner portion 65 screw threaded as at 12.

The aperture or opening 11 is adapted to receive the screw 7, the threads of which engage the threads 12 in said opening as clearly shown in Fig. 2. Upon one or more points 70 on the stop screw are formed longitudinally extending flat faces 13 adapted to be engaged by similar flat faces formed in an aperture 14 in the wheel through which aperture the screw projects and in which it is adapted 75 to freely slide. The provision of the flat faces 13 on the screw and the elongated aperture or opening 14 in the wheel causes the screw to turn with the wheel and at the same time slide longitudinally therein as it travels 80 through the aperture or opening 11. The wheel 8 has its periphery milled as shown at 15 and its diameter is greater than the width of the armor member 2 so that it projects beyond the opposite faces of the latter and 85 may be readily rotated between the thumb and the first finger. In order to prevent the screw from being turned or run out of the aperture 11 I head or upset its ends as shown at 16. 90

In use the stop screw 7 is first adjusted by rotating the wheel 8 and the device is then taken in hand and manipulated in the usual manner. By rotating the wheel in one direction the screw may be moved inwardly and 95 in the opposite direction it may be moved outwardly so that its inner end may be positioned at a greater or less distance from the inner edge of the arm or member 2 to limit the movement of the other arm or member 3 100 toward it and hence to limit the closing movement of the blades 6.

From the foregoing it will be seen that the construction disclosed is exceedingly simple 105 so that it may be produced at a comparatively small cost and will be durable in use and convenient to operate. The stop screw may be readily adjusted by simply rotating the wheel which can be quickly and easily done. 110

While I have shown and described my invention as applied to a button hole cutter, it

will be understood that it may be applied to a pair of shears, scissors or a similar instrument or tool in which it is desired to limit the closing movement of its arms or members.

5 Having thus described my invention what I claim is:

In a device of the character described, the combination of a pair of pivotally connected arms or members, one being formed in its 10 inner edge with a slot and with an intersecting opening, the latter having a screw threaded portion, a stop screw arranged in said opening and engaged with the threaded portion of the same and formed with longitudinally extending flattened portions or 15 faces, a wheel arranged in said slot and hav-

ing an aperture to slidably receive the screw, said aperture having flat portions to engage the flat faces of the screw whereby the screw will be caused to turn with the wheel and 20 permitted to slide longitudinally therethrough, and stop heads formed at the ends of the screw by upsetting the same and adapted to prevent the removal of the screw from the arm or member, substantially as 25 and for the purpose specified.

In testimony whereof I hereunto affix my signature in the presence of two witnesses.

GEORGE T. BARR.
